SILAS CHRISTOFFERSON, OF SAN FRANCISCO, CALIFORNIA.

ENGINE JACKET AND CYLINDER CONSTRUCTION.

1,248,808.

Specification of Letters Patent. Patented Dec. 4, 1917.

Application filed January 31, 1916. Serial No. 75,247.

To all whom it may concern:

Be it known that I, SILAS CHRISTOFFERSON, a citizen of the United States, residing at the city and county of San Francisco 5 and State of California, have invented certain new and useful Improvements in Engine Jackets and Cylinder Constructions, of which the following is a specification.

The present invention relates to improvements in internal combustion engines, particularly designed for aeroplane use, but equally as well adapted for general use, and has for its principal objects to provide an engine wherein the weight is materially reduced over that of the same size of engine now on the market; to provide a structure wherein the cylinders and inclosing water jackets are separate units detachably secured together and capable of being easily separated, enabling the cylinders to be readily replaced when worn and to be manufactured of a more durable and lighter weight material than is possible where the cylinders and jackets are constructed in a single one piece casting. Further objects being to provide an engine of the above type wherein the resultant strains of each explosion are received by the metal walls of the cylinder, and wherein the valves seat directly on the walls of the cylinder, thereby dispensing with all valve cages; to provide an engine wherein the cylinder and water jacket are secured together in such a manner as to provide fluid tight connections between the same and at the same time to permit of the expansion and contraction of the several parts.

With the above mentioned and other objects in view, the invention consists in the novel construction and combination of parts hereinafter described, illustrated in the accompanying drawings and pointed out in the claims hereto appended; it being understood that various changes in the proportion, form, size and minor details of construction may be resorted to without departing from the spirit or sacrificing any of the advantages of the invention.

To more fully comprehend the invention, reference is directed to the accompanying drawings, wherein—

Figure 1 is a view in end elevation, partly in section, of an engine cylinder and water jacket, disclosing an embodiment of my invention.

Fig. 2 is a view in side elevation, partly in section, of an embodiment of my invention, disclosing a water jacket casting having a pair of cylinders removably positioned therein.

Fig. 3 is an enlarged transverse broken vertical sectional view of an engine cylinder and water jacket casting constructed in accordance with my invention, disclosing more fully the formation and arrangement of the several parts, and the manner of detachably uniting the same together.

Referring more particularly to the several views of the drawings, wherein like characters of reference designate corresponding parts,—1 indicates the engine cylinders, preferably stamped from high carbon steel which insures maximum strength with minimum weight. Each cylinder is preferably formed on its side wall with the annular reinforcements 2 and 2', one positioned adjacent the top thereof and the other approximately midway of the side wall thereof. An annular flange 3' is formed at the base of the cylinders to provide a means for attaching the cylinders to an engine crank case or base, not shown. A water jacket casting 3, preferably of aluminum or any other suitable metal of lighter specific gravity than the cylinder, is formed with suitable openings in the lower portion or base thereof adapted to each receive an engine cylinder which is removably positioned therein. For convenience and to reduce the cost of manufacture, I have illustrated a single water jacket casting 3 as receiving a pair of cylinders, but it is to be understood that a single water jacket casting may be provided for each cylinder or that any number of cylinders may be enclosed by a single jacket casting.

The water jacket casting 3 is formed preferably at opposite sides with the open ended inlet and exhaust channels 4 and 5 which communicate at their inner ends with corresponding and registering inlet and exhaust ports, preferably formed in the head of each cylinder, and when the cylinders are properly positioned in the casting 3, with the respective inlet and exhaust openings in register, the walls 6 of the casting 3 surrounding the channels 4 and 5 rest on suitable gaskets 7 supported by suitable flanges 8 surrounding the inlet and exhaust ports of the cylinders.

Suitable flanged tubular couplings 9, one positioned in each inlet and exhaust port of the cylinders with the flanges thereof contacting with the annular seats 10, have 5 threaded connection with the respective walls 6 and detachably secure the top of the cylinders to the water jacket casting. Inwardly opening valves 11 control the respective inlet and exhaust ports of each 10 cylinder, the stems 12 thereof extending upwardly in the top portion or chamber 12' of the casting 3 and reciprocate in suitable bushings or guides 13 removably mounted in bores formed in the walls 6 surrounding the 15 channels 4 and 5, and extending through the top transverse wall 14 of the casting.

Projecting upwardly from the wall 14 into the chamber 12' are the arms 14' which pivotally mount the rocker arms 14² actuated by the cams on the rotary shaft 14³ and which coöperate with the upper ends of the valve stems and actuate the valves. Springs 14⁴ normally seat the valves and a removable cover 15 resting on the upstanding wall 16 of the jacket and which forms the chamber 12' incloses the valve operating mechanism and excludes the dust therefrom. Thumb nuts 17 which thread on studs 18 secure the removable cover 15 in place. By 20 mounting the valves and valve operating mechanism as described, the jacket may be removed from over a cylinder by first removing the valves and thence disconnecting the couplings 9 and without in any way disturbing the valve operating mechanism.

Suitable spark plug openings are provided in the cylinder walls below the inlet and exhaust openings and register with corresponding openings in the side wall of the 40 jacket casting 3. The flanged wall 19 of said casting 3 surrounding the openings therein rests against the reinforcement 2 of the cylinders and is detachably secured thereto by the flanged tubular couplings 20 45 threaded into the cylinders. The flange 21 of the couplings rest on gaskets 22 received in seats surrounding the spark plug openings. Suitable spark plugs or other ignition means 23 are threaded into the couplings 20, and while I have illustrated two spark plugs 50 for each cylinder, it is to be understood that one or more may be used, and that if but one is employed the other couplings 20, if such are employed, will provide a means 55 for attaching the jacket casting to the cylinders, and will be closed by suitable plugs, not shown. The lower side walls 24 of the jacket casting 3 extend longitudinally of the cylinder walls in spaced relation thereto 60 and terminate adjacent the reinforcement 2' on the cylinders, and the openings at the lower end thereof are preferably of an interior diameter to provide a snug fit over the reinforcement,—as in the drawings. Annular grooves 25 are provided on the inner

lower surface of the walls 24 adjacent to the reinforcement 2', and the same are formed with downwardly beveled lower walls 26 which tend to force the annular rubber packing 27 received in the grooves 25 against 70 the cylinder side walls and provide a fluid tight joint therebetween.

A cooling fluid is received in the chamber surrounding the cylinders and the same circulates through openings 28 in the jacket 75 casting 3. I have provided a construction wherein the cooling fluid is in close contact with the cylinder walls surrounding the valves, thereby maintaining the same cool at all times and preventing the warping 80 thereof.

By removing the valves and disconnecting and removing the threaded couplings 9 and 20, one or more of the cylinders may be removed from the jacket casting 3 for the 85 repairing or replacement thereof. It will be noted that I have provided a very light weight jacket for receiving the engine cylinders and have detachably united the parts together, whereby the cylinders may be removed therefrom when worn or to be repaired or cleaned, and in which new cylinders may be inserted when desired, thereby prolonging the life of the engine and maintaining the same highly efficient at little 90 cost. One or more cylinders may be removed from the jacket without in any way affecting or disturbing the valve operating mechanism.

Having thus described my invention, what 100 I claim as new and desire to protect by Letters Patent is:—

1. An internal combustion engine of the overhead valve type comprising a headed engine cylinder having inlet and exhaust 105 ports in the top wall thereof, a jacket for receiving and inclosing the upper end thereof, and the side walls of said cylinder and jacket being spaced from each other to provide a cooling chamber surrounding the cylinder, connections for circulating a cooling medium through said chamber, and means for detachably securing the cylinder and jacket together, with the top wall of said cylinder and the top 110 wall of said chamber in contact, said cylinder and jacket being capable of intact separation on the release of said securing means.

2. An internal combustion engine of the overhead valve type comprising a cylinder having inlet and exhaust ports in the head thereof, a jacket for receiving and inclosing the upper portion of the cylinder and the walls of said cylinder and jacket being spaced from each other to provide a cooling 120 chamber surrounding the cylinder, said jacket provided with inlet and exhaust channels communicating with the ports of said cylinder head, connections for circulating a cooling medium through said chamber, and 125

- means for detachably connecting said cylinder and jacket, said cylinder and jacket being capable of intact separation on the release of said connecting means.
5. An internal combustion engine comprising a jacket adapted for receiving and inclosing the upper end of an engine cylinder and provided with inlet and exhaust channels, a headed cylinder for positioning 10 at its upper end within said jacket with its upper end inclosed thereby, and provided with inlet and exhaust ports in its head for registering with the channels of said jacket, and the walls of said cylinder and jacket 15 being spaced from each other to provide a cooling chamber surrounding the cylinder, connections for circulating a cooling medium through said jacket, and means for detachably securing said cylinder within 20 said jacket, said cylinder and jacket being capable of intact separation on the release of said securing means.
4. An internal combustion engine of the overhead valve type, comprising a jacket 25 adapted for receiving the upper end of an engine cylinder and provided with inlet and exhaust channels, a headed cylinder for positioning at its upper end within said jacket and provided in its top wall with inlet and 30 exhaust ports for registering with the channels of said jacket, connections for circulating a cooling medium through said jacket, and means for detachably uniting said cylinder and jacket through said registering 35 channels and ports, said cylinder and jacket being capable of intact separation on the release of said uniting means.
5. An internal combustion engine comprising a jacket provided with a chamber 40 for receiving the upper end of a headed engine cylinder and formed with inlet and exhaust channels, a headed cylinder for reception in said chamber and provided in its head with inlet and exhaust ports, said cylinder and jacket provided with registering 45 ports in the side walls thereof, and means for detachably connecting said cylinder and jacket together through said registering ports in the side walls thereof, and at said 50 registering ports and channels in the head thereof, said cylinder and jacket being capable of intact separation on the release of said connecting means.
6. An internal combustion engine comprising a headed cylinder, a jacket provided 55 with a chamber for receiving the upper end of said cylinder and formed with connections for circulating a cooling medium therethrough, means for detachably connecting 60 said cylinder and jacket, the cylinder and jacket capable of intact separation on the release of said connecting means, and a friction packing at the base of said jacket for engaging the cylinder wall to provide a fluid 65 tight connection around the same.
7. An internal combustion engine of the overhead valve type, comprising a headed cylinder, provided with inlet and exhaust ports in the head thereof, a jacket provided with a chamber for receiving the upper end 70 of said cylinder, the side walls of said jacket and cylinder being spaced to provide a cooling chamber in direct contact with the cylinder wall, said jacket formed with connections for circulating a cooling medium 75 therethrough, and provided with inlet and exhaust channels, said jacket adapted for resting on the head of said cylinder with the side walls thereof extending over the side walls of the cylinder in spaced relation 80 thereto, a packing carried by the jacket for providing a fluid tight joint between the lower edge of side wall of said jacket and said cylinder, and means for detachably connecting said cylinder and jacket, said 85 cylinder and jacket adapted for intact separation on the release of said connecting means.
8. In combination with a headed engine cylinder formed with inlet and exhaust ports 90 in the head thereof, and having continuous substantially parallel side walls, a cooling jacket formed of a single piece of material for removably positioning thereover, and provided with a cylindrical opening for receiving and inclosing the upper end of said cylinder, said jacket provided with side walls for extending over the cylinder side walls in spaced relation thereto, said jacket 95 being further provided in its head with inlet 100 and exhaust channels for registering with the corresponding ports in the cylinder head, a packing carried by the jacket for engaging the cylinder side walls for providing a fluid tight joint between the base of said jacket 105 and said cylinder, and means for uniting the cylinder and jacket, said cylinder and jacket adapted for intact separation on the release of said uniting means.
9. In combination with an engine cylinder, 110 a cooling jacket for removably positioning thereover with the side wall thereof extending downwardly over the side cylinder walls, means for detachably securing the cylinder and jacket together, the interior wall surface 115 of said jacket side wall formed with an annular groove having a downwardly beveled side wall surface, and a packing supported in said groove for engaging the cylinder side wall to maintain a fluid tight joint between 120 the cylinder and lower surface of said jacket side wall, said packing adapted to be forced against the cylinder wall by the beveled surface of said groove on an internal pressure being exerted thereon from the interior of 125 said cooling jacket.
10. In combination with a headed engine cylinder having inlet and exhaust ports in the top wall thereof, a cooling jacket for removably positioning thereover, and pro- 130

- vided with a chamber for receiving and inclosing the headed end of the cylinder, the top wall of said chamber formed with inlet and exhaust channels for registering at one 5 end with said ports, means for detachably connecting said cylinder and jacket, with the top wall of said cylinder and top wall of said chamber in contact, means for admitting of a circulating of a cooling medium through 10 said jacket, and said cylinder and jacket being so formed that on the assembly thereof the registering ports thereof are surrounded by a channel for the circulation of a cooling medium.
- 15 11. In combination with a headed engine cylinder having inlet and exhaust ports in the head thereof, a cooling jacket for removably positioning thereover, and provided with a chamber for receiving and inclosing 20 the headed upper end of the cylinder and formed with inlet and exhaust channels in the head thereof for registering at one end with said ports, a valve for controlling each of said ports and opening inwardly and 25 downwardly into the cylinder and seating directly against the inner wall surface of the cylinder head surrounding said ports, said valves extending through said jacket, and valve operating means carried by said jacket.
- 30 12. In combination with a headed engine cylinder having inlet and exhaust ports in the head thereof, a cooling jacket for removably positioning thereover, and formed with inlet and exhaust channels in its head for 35 registering at one end and with said ports, the side walls of said jacket extending over the cylinder side wall, said jacket and cylinder contacting at a point surrounding said ports and channels, and means for detachably securing said cylinder and jacket together, said cylinder and jacket being capable of intact separation on the release of said securing means.
- 40 13. A jacket for receiving a headed engine cylinder adapted to be removably positioned therein, said jacket comprising a member provided with an opening through which the cylinder is adapted for insertion and the wall of which surrounding said cylinder 45 provides with the cylinder wall a cooling chamber, a wall surface at the top of said opening in said jacket for resting on the cylinder head, and a top wall providing with said intermediate wall a cooling chamber 50 communicating with said first mentioned cooling chamber, said last mentioned chamber formed with openings through which a cooling medium is circulated, and means for detachably securing said cylinder and jacket 55 together.
- 60 14. In combination with a headed engine cylinder having inlet and exhaust ports in the head thereof, a removable jacket for receiving the cylinder and formed with inlet 65 and exhaust channels for registering at one end with said ports and a portion of the side wall of said jacket, spaced from said cylinder wall and forming therewith a chamber, means for detachably securing said jacket and cylinder together, a valve for controlling each of said ports, valve operating mechanism carried by said jacket and removable therewith, and a removable cover for inclosing said valve operating mechanism. 70
- 75 15. In combination with an engine cylinder having inlet and exhaust ports in the head thereof, a jacket for receiving the cylinder and formed with inlet and exhaust channels for registering at one end with said ports, a portion of the side wall of said jacket spaced from said cylinder wall and forming therewith a chamber, tubular securing means for detachably securing the walls surrounding said registering ports and channels together, an inwardly opening valve seating directly on the cylinder head for controlling said ports, valve operating mechanism carried by said jacket above said cylinder, and a removable cover for inclosing said mechanism. 80
- 85 16. An internal combustion engine of the overhead valve type comprising a jacket provided with a chamber for detachably receiving the upper end of an engine cylinder inserted therein, and formed with fuel inlet and exhaust channels, a headed cylinder for insertion into said chamber and provided in its top wall with inlet and exhaust ports for registering with said channels, said cylinder 90 and jacket provided with registering ports in the side walls thereof, and tubular couplings for detachably connecting said cylinder and jacket through said registering ports in the side wall thereof and through said 95 registering ports and channels, said cylinder and jacket being capable of intact separation on the removal of said tubular couplings. 100
- 105 17. An internal combustion engine of the overhead valve type comprising a jacket provided with a chamber for detachably receiving the upper end of a headed engine cylinder and formed in its top wall with inlet and exhaust channels, a headed cylinder for insertion into said chamber and provided at its head with inlet and exhaust ports for registering with said channels, and tubular couplings inserted in said registering ports and channels for detachably uniting the cylinder and jacket, said cylinder and jacket 110 capable of intact separation on the removal of said tubular couplings. 115
- 120 18. An internal combustion engine comprising a stamped steel cylinder having a ported top wall, a separable cast jacket therefor for receiving and inclosing the upper portion thereof to provide with the cylinder wall a cooling chamber, said jacket provided with channels for communicating with the ports in the cylinder head and formed of a 125 130

material of lighter specific gravity than that forming the cylinder, and means for detachably securing said cylinder and jacket together, said cylinder and jacket capable of intact separation on the release of said securing means.

19. An internal combustion engine comprising a steel cylinder, a separable jacket for receiving and inclosing the upper portion thereof and formed of a material of lighter specific gravity than that forming the cylinder, the wall of said jacket forming a cooling chamber with the wall of the cylinder, and means for detachably securing the cylinder and jacket together, said cylinder and jacket capable of intact separation on the release of said securing means.

20. An internal combustion engine comprising a headed ported steel cylinder, a separable cast jacket therefor for receiving and inclosing the upper portion thereof to provide with the cylinder wall a cooling chamber, said jacket provided with channels for communicating with the ports in the cylinder and formed of a material of lighter specific gravity than that forming the cylinder, and means for detachably securing said cylinder and jacket together through said registering ports and channels, said cylinder and jacket capable of intact separation on the release of said securing means.

21. In an internal combustion engine of the overhead valve type comprising a headed stamped steel cylinder, a separable cast aluminum jacket provided with a chamber for receiving and inclosing the upper portion thereof, and means for detachably securing the cylinder and jacket together with the top wall of said chamber in contact with the top wall of said chamber, said cylinder

and jacket capable of intact separation on the release of said securing means.

22. An internal combustion engine of the overhead valve type comprising a headed steel cylinder formed with inlet and exhaust ports in the top wall thereof, a jacket therefor for receiving and inclosing the upper portion thereof to provide with the cylinder wall a cooling chamber, said jacket provided with channels for communicating with the ports in the cylinder head, means for detachably securing said cylinder and jacket together, valves for controlling the inlet and exhaust ports in said cylinder and adapted to open inwardly into the cylinder and to seat directly thereon and circumferential of the ports therein, and valve operating means carried by said jacket.

23. An internal combustion engine of the overhead valve type comprising a steel cylinder, a separable jacket for receiving and inclosing the upper portion thereof and formed of a material of lighter specific gravity than that forming the cylinder, said jacket forming with the cylinder wall a cooling chamber directly in contact with the cylinder wall, means for detachably securing the cylinder and jacket together, and a means carried by the base of the cylinder whereby the same may be secured to the engine crank case, said cylinder and jacket being capable of intact separation on the release of said securing means.

In testimony whereof I have signed my name to this specification in the presence of two subscribing witnesses.

SILAS CHRISTOFFERSON.
